(57) **CLAIM**

The ornamental design for a portable gas stove, as shown and described.

DESCRIPTION

FIG. 1 is a front perspective view of the embodiment 1, showing my new design;

FIG. 2 is a rear perspective view thereof of the embodiment 1;

FIG. 3 is a front view thereof of the embodiment 1;

FIG. 4 is a rear view thereof of the embodiment 1;

FIG. 5 is a left side view thereof of the embodiment 1;

FIG. 6 is a right side view thereof of the embodiment 1;

FIG. 7 is a top view thereof of the embodiment 1;

FIG. 8 is a bottom view thereof of the embodiment 1;

FIG. 9 is a front perspective view thereof of the embodiment 2;

FIG. 10 is a rear perspective view thereof of the embodiment 2;

FIG. 11 is a front view thereof of the embodiment 2;

FIG. 12 is a rear view thereof of the embodiment 2;

FIG. 13 is a left side view thereof of the embodiment 2;

FIG. 14 is a right side view thereof of the embodiment 2;

FIG. 15 is a top view thereof of the embodiment 2;

FIG. 16 is a bottom view thereof of the embodiment 2;

FIG. 17 is a perspective view showing the portable gas stove in a use state of the embodiment 2;

FIG. 18 is an enlarged detail view of area 18 in FIG. 1; and,

FIG. 19 is an enlarged detail view of area 19 in FIG. 10. The broken lines in the drawings illustrate the portions of the portable gas stove, which form no part of the claimed design. The dash-dot-dash broken lines encircling the enlarged views are for annotative purposes only and form no part of the claim thereof.
